CLAIM

The ornamental design for a head mounted display with flex cable, as shown and described.

DESCRIPTION

FIG. 1 is an isometric view of a first embodiment of a head mounted display with flex cable showing the new design.

FIG. 2 is a left side elevation view thereof.

FIG. 3 is a right side elevation view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is an isometric view of a second embodiment of a head mounted display with flex cable showing the new design.

FIG. 9 is a left side elevation view thereof.

FIG. 10 is a right side elevation view thereof.

FIG. 11 is a front elevation view thereof.

FIG. 12 is a rear elevation view thereof.

FIG. 13 is a top plan view thereof; and,

FIG. 14 is a bottom plan view thereof.

Any broken lines in the Figures are for illustrative purposes only and form no part of the claimed design.
